UNITED STATES PATENT OFFICE

155,161

DESIGN FOR A CLOTHES HAMPER

Iva Jacobson, Hamilton, Mont.

Application March 5, 1947, Serial No. 137,353

Term of patent 3½ years

(Cl. D58—4)

To all whom it may concern:

Be it known that I, Iva Jacobson, a citizen of the United States, residing at Hamilton, in the county of Ravalli and State of Montana, have invented a new, original, and ornamental Design for a Clothes Hamper, of which the following is a specification, reference being had to the accompanying drawing, forming part thereof.

Figure 3 is a rear elevational view thereof, and Figure 4 is a cross-sectional view, taken substantially in the plane of the line 4—4 in Figure 1.

I claim:

The ornamental design for a clothes hamper, as shown.

IV A JACOBSON.
